UNITED STATES PATENT OFFICE

ERNST SOHN, OF ST. LOUIS, MISSOURI.

DESIGN FOR AN ORNAMENTAL BOX.

SPECIFICATION forming part of Design No. 28,686, dated May 24, 1898.

Application filed April 6, 1898. Serial No. 676,718. Term of patent 3½ years.

To all whom it may concern:

Be it known that I, ERNST SOHN, of the city of St. Louis, State of Missouri, have invented a new and original Design for an Ornamental Box, of which the following is a full, clear, and exact description, reference being had to the accompanying drawing, forming a part hereof.

The figure is a perspective view of my ornamental box embodying my design.

As shown in the drawing, the leading or material feature of my design consists of a rectangular hollow body 1, having an open front. Arranged upon the center of the bottom of the frame or body 1 and against the back thereof is the outline of the figure 2, which is the subject of the picture, and appearing upon the back of the frame or body 1 is a cor-

rugated background 3. Extending from the top of the box or frame 1 to the sides thereof, at a slight distance in front of the figure 2, is suitable drapery 4, and immediately in front of this drapery, around the entire edge of the box or frame 1, is a continuous curved decoration 5, which is so arranged as that a clear and unobstructed view of the figure 2 is readily obtained.

I claim—

The design for an ornamental box, as herein shown and described.

In testimony whereof I affix my signature in presence of two witnesses.

ERNST SOHN.

Witnesses:

A. J. McCauley,
M. P. Smith.
